APPARATUS FOR THE DETERMINATION OF
BRINELL-NUMBERS

Stig Lennart E:Son Falk, Västerås, Sweden

Application August 1, 1932, Serial No. 627,211
In Sweden August 6, 1931

3 Claims. (Cl. 265—12)

For the determination of the hardness of various materials the so-called Brinell-method is made use of, among others. According to this method, a steel ball is pressed into the material in question under a certain load, which is selected so that the ball makes a remaining impression in the material. The penetration of the ball into the material is a measure of the hardness thereof, and the number of the hardness is indicated by the load applied to the ball, expressed in kilograms, divided by the curved surface, the so-called calotte formed in the material, expressed in square millimeters.

The invention relates to an apparatus for determining the hardness of a material by the Brinell method, which is simple and inexpensive in manufacture and which can be used for making a quick test in a work shop. It further has the advantage that it can be used over a wide test range; that the means for exerting the pressure can be easily calibrated; and that it is unstressed in the non-operative state of the apparatus.

In the accompanying drawing Fig. 1 represents a side view of an apparatus according to the invention and Fig. 2 shows a section through the handle on the line 2—2 of Fig. 1.

In the drawing, 1 and 2 designate the two shanks of the tongs which are pivotally connected with each other by means of a hardened pivot 3 running in steel bushings 4 pressed into the shanks. Attached to the shorter arm of the shank 1 is the anvil 5, and to the shorter arm of the shank 2 is secured a set-screw 6 carrying the exchangeable ball holder 7 adapted for different balls. This arrangement is well known and need not be further described here; it is not part of the present invention. Attached to the longer arm of the shank 1 by means of the screws 8 is an exchangeable and calibrated spring 9. At the free end the spring is provided with a handle 10 secured to the spring by means of the screws 11. Arranged on the handle 10 is an auxiliary handle or the like 12 pivoted to the handle 10 by means of screws 11. The longer arm of the shank 2 is provided at its free end with a strap 13 pivoted about the point 14 and constructed so as to form an abutment for the shank 1 when in the swung-up position shown in the drawing, so that the shanks 1 and 2 may be adjusted into a definite initial position relatively to each other. Furthermore, means are provided to limit the movement of the shanks toward each other in the use of the apparatus, said means comprising a set-screw 15 on the handle 10 and an abutment 16 on the shank 2.

In the use of the apparatus the object to be tested is inserted between the anvil 5 and the ball holder 7, the strap 13 is swung up, and the shank 1 is caused to bear on the strap 13 in the initial position. The screw 6 is then adjusted so that the ball touches the test piece, whereupon the strap 13 is swung down and the two shanks are approached to each other manually or by means of a clamp, until the set-screw 15 is brought into contact with the abutment 16. 10 Here, the force is applied between the auxiliary handle 12 and the free end of the shank 2, and on account of the suspension of the auxiliary handle at the point 11 and the limitation of the movement through the set-screw 15 and the 15 abutment 16, the force acting between the anvil and the ball holder will always be the same for a given spring. The impression is then measured as usual, and with the knowledge of the force acting between the ball holder and the 20 anvil, the Brinell-number may be calculated. For an accurate determination due regard is to be paid to the variation in the magnitude of the power caused by the steel ball being pressed into different materials in a varying degree. To 25 this end a table may be made up on the basis of comparative tests. For less accurate measurements, however, the apparatus may be used without taking this precaution and then offers the advantage of being readily transportable and 30 simple to use, so that the hardness of bulky material may be determined directly in the work shop.

What I claim is:—

1. Apparatus for the determination of the degree of hardness of materials in accordance with the so-called Brinell method comprising a pair of tong members pivoted to provide a pair of jaws, a ball holder and an anvil positioned on the opposing jaws, respectively, and means to subject the ball to be tested to a controllable spring pressure, said means comprising an exchangeable and calibrated flat spring member extended in prolongation of the shank of one of said tong members and so arranged as to be 45 unstressed in its initial position.

2. Apparatus for the determination of the degree of hardness of materials in accordance with the so-called Brinell method comprising a pair of tong members pivoted to provide a pair of jaws, a ball holder and an anvil positioned on the opposing jaws, respectively, means to subject the ball to be tested to a controllable spring pressure, said means comprising an exchangeable and calibrated flat spring member extended in 55

prolongation of the shank of one of said tong members, and means to prevent the spring from being stressed in the initial position of said spring.

5 3. Apparatus for the determination of the degree of hardness of materials in accordance with the so-called Brinell method comprising a pair of tong members pivoted to provide a pair of jaws, a ball holder and an anvil positioned on 10 the opposing jaws, respectively, means to subject

the ball to be tested to a controllable spring pressure, said means comprising an exchangeable and calibrated flat spring member extended in prolongation of the shank of one of said tong members, and means including a latch member pivotally attached to the extended shank of the other of said tong members to prevent the spring from being stressed in the initial position of said spring. 5
